COMBINED LETTER OPENER AND MEASURING INSTRUMENT

Robert H. C. M. Daenen, Erembodegem, Belgium,
assignor to Dart Industries Inc., Los Angeles, Calif.

Filed Aug. 10, 1973, Ser. No. 387,307

Term of patent 14 years

Int. Cl. D8—05

U.S. Cl. D8—104

FIG. 1.

FIG. 2.

FIG. 3.

FIG. 4.

FIG. 5.

FIG. 6.

FIG. 1 is a front elevational view of a combined letter opener and measuring instrument showing my new design;

FIG. 2 is a right side elevational view;

FIG. 3 is a bottom plan view;

FIG. 4 is a rear elevational view;

FIG. 5 is a left side elevational view; and

FIG. 6 is a top plan view.

I claim:

The ornamental design for a combined letter opener and measuring instrument, substantially as shown.
